DESIGN FOR A PAPER BOTTLE OR SIMILAR CONTAINER

Lydia B. Koch, New York, N. Y.

Application February 1, 1938, Serial No. 74,769

Term of patent 14 years

To all whom it may concern:

Be it known that I, Lydia B. Koch, a citizen of the United States, residing at New York, N. Y., in the county and State of New York, have invented a new, original, and ornamental Design for a Paper Bottle or Similar Container, of which the following is a specification, reference being had to the accompanying drawing, forming a part thereof, and in which:—

The figure is a perspective view of a paper bottle or similar container, showing my new design.

The characteristic features of the new design reside in the container having a smooth cylin-

drical lower portion, embellished at its upper edge with two parallel circumambient lines enclosing a crenulated band, above which is a conical portion presenting a series—multiple of vertical scores arranged in staggered relation, and a plurality of indented flutes arcuately curved at their tops, adjacent the container opening, and gradually blending therebelow into the surface above the band.

I claim:

The ornamental design for a paper bottle or similar container, as shown and described.

LYDIA B. KOCH.
